UNITED STATES PATENT OFFICE.

ALOIS J. RHEINBERGER, OF NEW YORK, N. Y.

SECTIONAL BOOTH.

Application filed November 8, 1922. Serial No. 599,618.

To all whom it may concern:

Be it known that I, ALOIS J. RHEINBERGER, a citizen of the United States, and a resident of New York, in the county and State of New York, have invented certain new and useful Improvements in Sectional Booths, of which the following is a specification.

This invention relates to improvements in screen enclosed compartments such as are the vogue in beauty parlors, hair dressing, chiropodist and like establishments in which it is desirable to seclude the parties undergoing treatment from the view of visitors and others, thereby avoiding unnecessary publicity and exposure.

Such screens are made in a variety of material, relatively thin, light and strong, as pongee silk, etc., admitting light but obscuring the parties within the walls of the enclosed space, which is entirely open at the top for ventilation and air circulation throughout the premises in which the booths are located, the screen walls however preventing a draft or direct current of air from striking the individual.

The main purpose of the invention is to produce an artistic frame of suitable rigidity from which the draperies may be securely suspended, and which may be moved about the premises as desired.

Another object is to provide a sectional frame which may be readily assembled or dismounted without the use of tools or implements of any kind, thus enabling a booth to be quickly erected or, when not in use, knocked down and stored in a minimum of space, all without requiring the services of a skilled mechanic.

A further aim is in the provision of a novel form of joint connection for the several frame members which permits adding other booth sections in an inexpensive and practical manner, all of the standards and beams being made of ordinary commercial material, rendering the booth relatively inexpensive to construct.

These and other unspecified aims, objects and purposes, which will become later apparent, are attained by the novel construction, and arrangement of parts hereinafter described and shown in the accompanying drawing, forming a material part of this disclosure, and in which:

Figure 1 is a general perspective view of a conventional type of booth made in accordance with the invention.

Figure 2 is an enlarged fragmentary perspective view showing the details of its corner construction, looking from the inner side.

Figure 3 is a partial side elevational, partial sectional view of the corner elements as assembled, parts being broken away to show the inner construction.

Figure 4 is a top plan view of the same.

It will be obvious that such booths may be of any reasonable size and that the screen walls may be curved as well as straight, as shown in Figure 1, the view illustrating a substantially square compartment enclosed by curtain screens 10 on three sides and essentially fixed panels 11 at the front, between which is an opening normally closed by curtains 12.

The frame consists of uprights 14, preferably made of tubes in order to secure lightness and rigidity, these uprights being fixed at their lower ends in pipe flanges or hubbed discs 15 resting on the surface of the floor to which they may be fastened as desired.

The upper ends of the uprights are furnished with ornamental knobs or terminals 16, their projecting plugs 17 being screw-threaded into socket sleeves 18 surrounding the upper portions of the uprights, the ends of the plugs abutting the tops of the vertical corner tubes as shown.

The sleeves 18 are formed with brackets 21 having raised rectangular side walls 22, in the upper edges of which are recesses 23 at their centers.

Tubular beams 24 are cut transversely across near their ends, the kerfs 25 being suited to engage the sides 22 of the brackets and their depth made equal to one half the diameter of the tubes, which fit the recesses 23 of the brackets so as to be held laterally in position by them.

A similar arrangement of brackets and beams is provided near the bottoms of the posts, except at the front, where short posts 20 support the inner ends of the lower beams as shown.

Thus the tubular beams engage at their ends in the brackets as described and are held from either longitudinal or transverse movement, being firmly supported but obviously may be released by raising the tube vertically, co-incidently clearing the kerfs and corresponding bracket recesses.

It will also be apparent that when the tubes engage the brackets, the uprights are

held in a vertical position, the tubes acting as braces, and it will be evident that the beams may be engaged on one or more sides of the brackets, thus forming a rectangular structure to which additions may be made in an obvious manner in any direction.

It is to be understood that the brackets may be circular or polygonal as well as square, and that the method of attachment 10 to the uprights is merely illustrative, other means for accomplishing the same purpose being within the scope of the invention.

The several uprights have longitudinal slots 26 formed in their walls, near the lower 15 ends of the sleeves 18, and fitted to pass through these slots are bars 27 having notches 28 near their ends, these notches removably engaging the wall of the tube while the end portions of the bars beyond the notches 20 are entered within the tube as best shown in Figure 3, and it will be seen that the slots 26 are in vertical register with the centers of the recesses 23, thereby maintaining the bars 27 in spaced parallel adjustment 25 with the beams 24. In a like manner other similar bars 27' are attached to the posts above the lower beams 24'.

It will be apparent that the bars may be raised and removed from the uprights in essentially the same manner as the beams, therefore constituting a frame structure 30 easily assembled or "knocked down" at will, and further that the lower ends of the sleeves 18 may rest upon the upper edges of the bars, holding them in the slots which are thus covered by the sleeves.

The bars 27 serve as supports for a plurality of rings 29 secured to the upper and lower edges of the screen curtains 10 so that 40 the latter may be readily moved sidewise as well as the curtains 12 at the front, but if preferred the said screen edges may be hemmed as at 30 and the bars passed therethrough as indicated at the tops of the 45 panels 11.

From the foregoing it will be seen that the booth may be constructed of four of each of the uprights, with their beams and bars, and that additional sections require 50 only two uprights and corresponding beams and bars, rendering the structure economical, and avoiding the use of all forms of fastening means as bolts, screws and rivets.

Although I have described my improve-

ments with considerable detail and with respect to certain particular forms of my invention, I do not desire to be limited to such details since many changes and modifications may well be made without departing from the spirit and scope of my invention in its broadest aspect.

Having thus described my invention, what I claim as new and desire to secure by Letters Patent, is:—

1. A booth comprising a plurality of tubular uprights having removable caps, transverse tubular beams removably engaged with said uprights, rectangular bars interengaged with said uprights, said bars being spaced in parallel adjacently below 70 said tubes, and textile fabrics adjustably suspended from said bars to form the walls of the booth.

2. A sectional booth comprising tubular corner posts, flanged feet at the bottoms 75 thereof, brackets fixed on said posts near their upper ends, tubular beams resting in said brackets, means formed cooperatively with said brackets and beams to prevent relative movement, and notched bars engaging 80 slots in the walls of said posts, said bars supporting draperies constituting the walls of the booth.

3. A booth frame construction comprising a tubular post, a rectangular bracket 85 fixed on said post, said bracket having upstanding edges containing depressions in the center of each of their sides, and tubular beams slotted to engage said edges and to be received in the mentioned depressions 90 therein.

4. A booth frame construction comprising a tubular post having a plurality of longitudinal slots through its walls near the upper end thereof, a sleeve fixed on said post 95 to extend above the top thereof, a bracket carried by said sleeve, said bracket having raised marginal edges, a knob fixed in said sleeve to rest on said post, tubular beams having transverse recesses fitting the edges 100 of said bracket, said edges being recessed to receive the beams, and bars notched near their ends to pass through the slots in said post and engage therein whereby the bars are supported.

In testimony whereof I have signed my name to this application.

ALOIS J. RHEINBERGER.
